CLAIM

I claim the ornamental design for a handle, as shown and described.

DESCRIPTION

FIG. 1 is a top perspective view of a handle showing the new design in a first embodiment;

FIG. 2 is a front elevation view thereof, where a rear elevation view is a mirror image;

FIG. 3 is a right side elevation view thereof, where the left side elevation view is identical thereto;

FIG. 4 is a top plan view thereof;

FIG. 5 is a bottom plan view thereof;

FIG. 6 is a top perspective view of a second embodiment of the handle showing the new design in a second embodiment;

FIG. 7 is a front elevation view thereof, where a rear elevation view is a mirror image;

FIG. 8 is a right side elevation view thereof, where the left side elevation view is identical thereto;

FIG. 9 is a top plan view thereof; and,

FIG. 10 is a bottom plan view thereof.

The dashed broken lines shown in the drawings depict portions of the handle that form no part of the claimed design. FIGS. 1, 2, 4, 5, 6, 7, 9, and 10 each include one or more symbolic breaks in length indicated by a pair of break lines and corresponding bracket, where the appearance of any portion of the article between the break lines forms no part of the claimed design.

1 Claim, 6 Drawing Sheets
